UNITED STATES PATENT OFFICE

PETER C. C. FRIDERICHSEN, OF INDEPENDENCE, MISSOURI

DESIGN FOR A FLOOR TILE OR SIMILAR ARTICLE

Application filed October 4, 1929. Serial No. 32,948. Term of patent 14 years.

To all whom it may concern:

Be it known that I, PETER C. C. FRIDERICHSEN, a subject of the King of Denmark, residing at Independence, in the county of Jackson and State of Missouri, have invented a new, original, and ornamental Design for Floor Tile or Similar Article, of which the following is a specification, reference being had to the accompanying drawing, forming a part hereof.

The figure is a top plan view of a floor tile or similar article, showing my new design.

What I claim is:

The ornamental design for a floor tile or similar article as shown.

PETER C. C. FRIDERICHSEN.
